(57) **CLAIM**

The ornamental design for a locking device for double doors, as shown and described.

DESCRIPTION

FIG. 1 is a top perspective view of a locking device for double doors, showing our new design in a used condition; FIG. 2 is a top perspective view thereof; FIG. 3 is a top plan view thereof; FIG. 4 is a front elevation view thereof, the rear elevation view being an identical image thereof; FIG. 5 is a bottom plan view thereof; and, FIG. 6 is a right-side elevation view thereof, the left-side view being an identical image thereof. The broken lines shown in the drawings depict environmental subject matter that forms no part of the claimed design.
